DESIGN FOR A DOG BED

Robert L. Richardson, Eden, N. Y.

Application September 25, 1940, Serial No. 95,358

Term of patent 7 years

To all whom it may concern:

Be it known that I, Robert L. Richardson, a citizen of the United States, residing at Eden, in the county of Erie and State of New York, have invented a new, original, and ornamental Design for a Dog Bed, of which the following is a specification, reference being had to the accompanying drawing, forming a part thereof.

Figure 1 is a perspective view of the dog bed embodying my design. Figure 2 is a rear view thereof. Figure 3 is an end view of the same.

I claim:

The ornamental design for a dog bed, substantially as shown.

ROBERT L. RICHARDSON.
